CLAIM

The ornamental design for a barrier net for suspension between the passenger and trunk compartment of a vehicle, as shown and described.

DESCRIPTION

FIG. 1 is a front elevation view of a barrier net for suspension between the passenger and trunk compartment of a vehicle showing my new design;

FIG. 2 is a rear elevation view thereof;

FIG. 3 is a side elevation view thereof, the opposite side being a mirror image of that shown;

FIG. 4 is a top plan view thereof;

FIG. 5 is a bottom plan view thereof;

FIG. 6 is a front elevation view of a barrier net for suspension between the passenger and trunk compartment of a vehicle showing a second embodiment of my new design;

FIG. 7 is a rear elevation view of FIG. 6;

FIG. 8 is a side elevation view of FIG. 6, the opposite side being a mirror image of that shown;

FIG. 9 is a top plan view of FIG. 6; and,

FIG. 10 is a bottom plan view of FIG. 6.
